Fig. 1

Fig. 2

Fig. 3

FIG. 1 is a front elevational view of a battery cell tester showing my new design, with the probe arm separated from the case;

FIG. 2 is a perspective view thereof with the probe arm in place on the bottom of the case; and

FIG. 3 is a perspective view showing the two mating parts of the FIG. 1 instrument, as separated.

The essential features of my design reside in the portions shown in full lines in the drawings.

The rear and side of the article not shown are substantially plain and unornamented.

I claim:

The ornamental design for the battery cell tester, as shown and described.
